UNITED STATES PATENT OFFICE.

MICHAEL KUTCHER, OF PHILADELPHIA, PENNSYLVANIA.

FIREARM.

SPECIFICATION forming part of Letters Patent No. 787,626, dated April 18, 1905.

Application filed January 23, 1904. Serial No. 190,306.

To all whom it may concern:

Be it known that I, MICHAEL KUTCHER, a subject of the Emperor of Austria-Hungary, and a resident of Philadelphia, in the county 5 of Philadelphia, State of Pennsylvania, have invented certain new and useful Improvements in Firearms, of which the following is a full, clear, and exact description when taken in connection with the accompanying drawings, 10 which form a part of this specification, and represent, in—

Figure 1, a broken view, in side elevation, of a firearm embodying my invention; Fig. 2, a broken view of the gun, partly in vertical longitudinal section and partly in elevation, shown in its closed position; Fig. 3, a broken view of the gun, partly in side elevation and partly in vertical longitudinal section, showing the breech-block partly opened; 15 Fig. 4, a similar view showing the breech-block and carrier in their open position; Fig. 5, a similar view showing the breech-block partly closed; Fig. 6, a transverse section on the line of the rear end of the barrel of the 20 gun looking back; Fig. 7, a similar transverse section on a line through the pivot of the firing-pin lock; Fig. 8, a broken detached reversed side view of the rear end of the action-bar; Fig. 9, a broken view, in vertical 25 longitudinal section, showing the firing-pin retracted and locked by a firing-pin lock; Fig. 10, a horizontal section through the breech-block and illustrating the ejector carried thereby; Fig. 11, a broken view, in vertical 30 longitudinal section, showing the firing-pin unlocked by the depression of the end of the firing-pin lock under the action of the carrier; Fig. 12, a detail perspective view of the 35 pawl carried by the breech-block for engaging the action-bar; Fig. 13, a detail view of the 40 firing-pin.

My invention relates to an improvement in magazine-firearms of the type in which the action mechanism is actuated by means of a 45 sliding handle which is reciprocated back and forth in a line parallel with the axial line of the gun-barrel, the object of my invention being to increase the efficiency and safety of these arms.

With these ends in view my invention con-

sists in certain details of construction and combinational parts, as will be hereinafter described, and pointed out in the claims.

Referring to the drawings, 1 indicates the stock of the gun; 2, the barrel; 3, the magazine; 4, the casing containing the firing and loading mechanism, and 5 the firing-hammer.

B is the breech-block, adapted to move back and forth in the casing 4.

A is an action-bar having the sliding sleeve 60 A' secured thereto, said sleeve being designed to be reciprocated back and forth upon the magazine 3 in a line parallel with the axial line of the gun-barrel 2. The action-bar trav-

els in a groove A² in the inner wall of the casing 4 and has a recess A³ in its upper edge, said recess having rearwardly-inclined edges A⁵ and A⁶. The reciprocation of the action-bar is imparted to the breech-block through the medium of a pawl B', which is pivoted to 70 the breech-block on the side adjacent the action-bar and adapted to enter the recess A³ and be confined therein during the forward and backward movement of the action-bar. The pawl B' has an outwardly-extending toe 75

which is formed with the horizontal portion B³ and the vertical portion B⁴, said vertical portion having its limiting ends B⁵ and B⁶ inclined rearwardly with respect to the gun to correspond with the inclined ends A⁵ and A⁶ 80

of the recess A³. The pawl B' is adapted to lie normally on the upper surface of the action-bar until said bar is moved rearwardly and the recess A³ and the portion B⁴ of the pawl B' register. The portion B⁴ of the pawl 85

B' will then fall by gravity into the recess A³, which is of somewhat greater length than the portion B⁴, and by reason of the corresponding inclined edges B⁵ and A⁵ of the pawl and action-bar, respectively, a firm engagement 90 will be produced between the action-bar and the breech-block through the medium of the pawl, whereby the continued movements of the action-bar will produce the rearward excursion of the breech-block. During the forward movement of the action-bar the pawl B' is retained in engagement with the action-bar by the upper wall of the groove A² against the tendency of the coacting inclined surfaces B⁶ and A⁶ to throw the pawl upwardly. This 100

engagement between action-bar and pawl is maintained until the forward excursion of the breech-block is complete, when the pawl will pass directly beneath the cut-away portion 6 of the casing and be forced by the coacting inclined edges B⁶ and A⁶ into said cut-away portion, thereby removing the operative engagement between the action-bar and breech-block.

- The mechanism by which the cartridge is taken from the magazine 3 and thrown into position in front of the breech-block B, and thereby pushed into the breech of the barrel, consists of a vertically-oscillating carrier C, 5 pivoted in the casing 4, near the rear therof and directly beneath the breech-block. This carrier is adapted to be intermittently raised and lowered by means of the stud A⁴ projecting from the action-bar and moving in the cam-groove C' in the adjacent side of the carrier as the action-bar and breech-block advance or retreat. The lower side of the casing 4 is cut away to permit the carrier C to lower into the position shown in Fig. 4 and to also permit the 5 cartridges to be inserted into the magazine through the recess thus formed when the carrier is in the position shown in Fig. 2. The forward end of the groove C' extends sharply upward a short distance, as shown in Fig. 8, so that the initial rearward movement of the action-bar causes the carrier to move down a short distance until the stud on the action-bar is free to move rearwardly in the prolonged horizontal portion of the groove C', such 5 movement of the stud in said horizontal portion of the groove C' being without appreciable effect to further depress the carrier. The initial movement of the carrier just described serves to remove the main portion thereof from behind the enlarged head B² of the breech-block and leaves said breech-block free to move on its rearward excursion. The rear end of the groove C' curves sharply upward, so that just as the breech-block and action-bar approach the position shown in Fig. 4 the carrier will again be moved quickly downward into the position therein indicated, so that its upper surface is below the opening in the magazine 3, through which the cartridges 5 are expelled by means of the well-known coil-spring contained in said magazine. Immediately the forward excursion of the breech-block is begun by the forward movement of the action-bar the carrier assumes the position shown in Fig. 5 and remains in said position until the breech-block is completely closed, when a further forward movement of the action-bar will be without effect on the breech-block by reason of the fact that the pawl B' 5 will move upwardly into the cut-away portion 6 of the casing 4 and remove itself from the influence of said action-bar. This final movement of the action-bar completely closes the carrier into the position shown in Fig. 2.
- The device whereby the cartridges are held

in the magazine until such time as it is necessary to allow one to slip out are two springs D and D'. These springs are set in recesses in the opposite sides of the casing 4, their rear ends being fastened and their front ends free, 70 said front ends normally standing above the recess in which the springs are set and which act as a stop to prevent the cartridges from being expelled from the magazine until they are depressed. The longitudinal edges of the 75 springs D and D' are slightly beveled, so that the carrier in its downward movement will depress the said springs, causing the same to retreat away from behind the cartridge, thereby permitting it to be expelled against the 80 upwardly-extending portion C² of the carrier, which is then directly behind it. When the breech-block approaches the position shown in Fig. 4, the carrier C, as heretofore stated, is quickly lowered and the cartridge will be 85 expelled from the magazine and rest upon the upper surface of the carrier. The springs D and D' will then return to their normal position and prevent the next cartridge in the magazine from being expelled until the proper 90 time.

The breech-block D is provided with the two yielding extractors E and E'. The extractor E' is slightly less yielding than the extractor E and has a curve forwardly-extending portion E², adapted to grip the rim of the cartridge. The extractor E consists of a spring-arm having an inwardly-projecting end adapted to pass in front of the rim of the cartridge when the breech-block is closed. When the 100 breech-block is opened after firing, the extractors E and E' will draw the empty cartridge rearwardly until the rim of the cartridge is engaged by the stud G, which lies in the path of the travel of the cartridges in 105 the rearward excursion of the breech-block. The aforesaid engagement of the stud G with the rim of the cartridge will cause the cartridge to be violently released from the grip of the extractor E' and thrown outwardly 110 through the recess in the casing caused by the opening of the breech-block.

The cartridge-guide K, formed of a thin plate of sheet metal, is secured to the carrier C by the friction-pivot K', by which it is held 115 in its projected or operating position during the oscillation of the carrier. The friction incident to the pivot K' is sufficient to hold same in its projected position without other aid. The guide is lifted into that position by 120 means of the stationary lifting-pin K³, mounted in and projecting inwardly from the right-hand wall of the casing 4. The said pin co-acts with the lower edge of the guide K at the rear. When in the action of the gun the carrier swings down preparatory to receiving a cartridge, the lower edge of the guide engages with the pin K³, whereby the frictional restraint placed upon the guide by the pivot K' 125 is overcome, so that the guide is lifted into 130

its projected position, (shown in Fig. 4,) in which it is held by friction, the engagement of the guide with the pin taking place some time before the carrier reaches its fully-depressed position. On the other hand, when the carrier begins to move to its raised position the guide K is immediately cleared of the pin K'; but the guide being supported by friction does not fall back, but remains in its projected position and performs its function of preventing the lateral displacement of the cartridge from the carrier. However, after the cartridges have been partially introduced into the chamber of the gun-barrel the forward end of the breech-block B engages with the upper edge of the guide near the forward end thereof and forces the guide downward into its retired position against the restraint of the friction-pivot K'.
 The breech-block B carries the firing-pin F in a central longitudinal chamber. The breech-block also carries the firing-pin lock L, which is located in a vertical longitudinal slot L', formed in the lower face of the breech-block at a point to one side of the longitudinal center thereof, the lock being pivoted on the horizontal pin L'', which also serves as a pivot for the pawl B'. The said pivot-pin L'' lies in a recess F' in the firing-pin to prevent the firing-pin from falling out rearwardly from its chamber in the breech-block. The lock L consists of a heavy flat plate formed with the retracting-cam L³ and the lifting-cam L⁴ and a straight locking edge L⁵ and works in a recess F², formed by facing away a portion of one side of the cylindrical butt F³ of the firing-pin, which is shown in Fig. 13. The rear end of the recess F² terminates in a wall comprising the square locking-shoulder F⁴ and a beveled retracting-shoulder F⁵. The lock L is forced into and maintained in its retired position by the carrier, which as it goes into its fully-closed position engages with the lower edge of the forward end of the lock at the point L⁶, whereby the spring L⁷ is compressed and the lock swung on its pin L², so as to depress its rear end and clear the square locking edge L⁵ thereof from the locking-shoulder F⁴ of the firing-pin, which is thus left free to leap forward when struck by the hammer 5. The moment, however, that the carrier begins its descent the spring L⁷ asserts itself, swings the firing-pin lock on its pivot, depressing its forward end and lifting its rear end into the position shown in Fig. 9. During the lifting of the rear end of the lock its retracting-cam L³ engages the retracting-shoulder F⁵ of the firing-pin, causing the same to be positively retracted by the spring L⁷. The firing-pin having been thus retracted, the spring L⁷ lifts the rear end of the lock still farther, so that the square locking edge L⁵ is brought into direct opposition with the square locking-shoulder of the firing-pin, as shown in Fig. 9. If for any reason,

however, the spring L⁷ should not act in swinging the lock for retraction and locking of the firing-pin, the lifting-cam L⁴ of the lock will in the rearward excursion of the breech-block B engage with the upper face 70 of the rear end of the carrier and positively lift the rear end of the lock, so as to retract and lock the pin, whereby the retraction and locking of the pin is insured even though the spring L⁷ may fail of performing that function. After the breech-block has reached the limit of its forward excursion the carrier rises and engages with the forward end of the lock, overcoming the tension of the spring L⁷ and depressing its rear end for unlocking 80 the firing-pin. It will be understood, of course, that the carrier does not act upon the lock until nothing remains to be done in fully closing the gun except the final movement of the carrier, the idea being to hold the firing-pin locked until the gun is virtually closed.

The sliding sleeve A' has pivoted thereon the spring-actuated catch A⁴, which is adapted to snap in front of the annular projection A⁵ on the magazine 3 and prevent the accidental rearward movement of the sleeve and action-bar during the operation of firing or at any undesired moment.

I claim—

1. In a magazine-firearm, the combination 95 of a longitudinally - reciprocating breech-block, a slideable action-bar provided with a recess, a pawl pivoted to the breech-block having an offset extending laterally from the body of the pawl adapted to engage the recess in the action-bar, corresponding rearwardly-inclined edges at the forward ends of the recess and the offset of the pawl whereby said action-bar and pawl are held in engagement during rearward movement of the action-bar, corresponding rearwardly-inclined edges at the rear end of the recess and the offset of the pawl, a casing inclosing the breech mechanism of the gun and provided with a longitudinal groove in which the action-bar slides whereby the action-bar and the offset of the pawl are held in engagement by the upper side of the groove in the casing against the tendency of the rear inclined edges of the recess and the offset of the pawl to 100 separate the parts on forward movement of the action-bar, and means for releasing the engagement between the offset of the pawl and the recess at the termination of the forward movement of the action-bar. 105

2. In a magazine-firearm, the combination 110 of a longitudinally - reciprocating breech-block, a slideable action-bar provided with a recess, a pawl pivoted to the breech-block having an offset extending laterally from the 115 body of the pawl adapted to engage the recess in the action-bar, corresponding rearwardly-inclined edges at the forward ends of the recess and the offset of the pawl whereby said action-bar and pawl are held in engagement 120

during rearward movement of the action-bar, corresponding rearwardly-inclined edges at the rear end of the recess and the offset of the pawl, a casing inclosing the breech mechanism of the gun and provided with a longitudinal groove in which the action-bar slides whereby the action-bar and the offset of the pawl are held in engagement by the upper side of the groove in the casing against the 5 tendency of the rear inclined edges of the recess and the offset of the pawl to separate the parts on forward movement of the action-bar, 10

and a cut-away portion in the casing at the forward end of the groove adapted to receive the offset of the pawl at the termination of 15 the forward movement of the action-bar whereby the engagement between the pawl and action-bar is released.

In testimony whereof I affix my signature in presence of two witnesses.

MICHAEL KUTCHER.
